PUNCH PRESS HAVING MAGNETIC
REACTIVE FORCES

Jacob Rabinow, Takoma Park, Md., assignor to Rabinow
Engineering Co., Inc., Rockville, Md.
Filed May 12, 1960, Ser. No. 28,721
7 Claims. (Cl. 83—382)

This invention relates to presses and more particularly to presses for large area work pieces.

Deep throat presses, for instance punch presses, must be made structurally heavy in order to withstand reactive press loading. Such presses in current industrial and commercial use have exceedingly heavy frames. As a result, they are expensive and comparatively difficult to move.

An object of my invention is to make it possible to construct a comparatively lightweight punch press with a deep unobstructed throat. This is accomplished by the inclusion of means, preferably located in the region of the tool holder of the punch press, for magnetically transmitting reactive press forces between the upper and lower part of the throat. The effect is an electromagnetic clamp which prevents spreading of the throat.

Although the design of different manufacturers' makes of presses varies somewhat, the frames of all presses, to my knowledge, are made sufficiently strong to withstand press reactive forces within a given parameter. My invention deviates from accepted design practices by using a lightweight frame in place of the usual heavy casting, as the frame of the press. Essentially the only function of the top part of the frame of my press is to support and align the tool holder, and to serve as a portion of the means for establishing a favorable flux path between the base of the frame and the upper part of the frame. These means may take the form of an electromagnet and a highly permeable metal member.

Although the principles of the invention are very well compatible with a number of different types of presses such as for metal bending, metal punching presses and others, the subsequent description deals only with punch presses since such presses represent one preferred area of use of the invention. It is to be clearly understood that the illustrated form of the invention is given by way of example only.

Other objectives, features and advantages of this invention will become evident in following the description of the illustrated form of the invention.

FIGURE 1 is a diagrammatic side elevational view of a press constructed in accordance with the invention.

FIGURE 2 is a diagrammatic front elevational view of the press in FIGURE 1, the controls for the press being only schematically represented.

In the accompanying drawing, I have shown press 10 mounted on a suitable support such as table 12. Press 10 is intended to replace heavy industrial presses or commercial presses which are ordinarily found in machine shops, manufacturing plants, etc. However, the invention may also be applied to hobbyists presses or may take the form of an attachment for an ordinary, conventional press in order to increase the tolerable loading of the frame of the press.

Press frame 14 has a first, upper frame member 16 and a lower, second frame member 18 joined together at their inner ends by frame member 20. The upper frame member 16 is in the form of a simple truss with a bearing plate 22 at the outer end. Frame member 20 may be a post or simply a U-shaped member (FIGURE 2) secured at its lower end to frame member 18 shown as a flat bed plate. Frame 14 is essentially C-shaped

2

when viewed from the side, and it has a deep throat 24 to receive comparatively large area work pieces W.

Electromagnets 26 and 28 are secured to the frame members 16 and 18, and they are spaced from each other to form a flux gap 30. Tool holder 32 is conventional, and it is secured to the piston of a tool holder actuation cylinder 34 located between the two poles of electromagnet 26. Cylinder 34 is secured to the bearing plate 22. Plate 36 is adjustably attached to bearing plate 22 and the means for achieving this may vary. I have illustrated two screws 38 and 40 in tapped openings in bearing plate 22 and swivably connected to plate 36, however it will become at once evident that the screws may be substituted by a single positioning hydraulic cylinder or a plurality of hydraulic cylinders, pneumatic cylinders, etc. where high speed operation is desirable.

The lower electromagnet 28 has two pole pieces directly opposing the pole pieces of electromagnet 26, and a flux return plate 42 whose function is similar to plate 36. The die or die holder 44 is disposed between the pole pieces of the lower electromagnet 28, and like tool holder 32, is conventional.

FIGURE 2 shows a conventional source 46 of fluid under pressure, for example air or liquid, and a control valve 48 connected to source 46 by way of conduits 50. Valve 48 is a three-way valve, however the actual hydraulic circuit is not considered to be critical. Conduits 52 and 54 extend from valve 48 to cylinder 34 in order to raise and lower the tool holder 32 in response to operation of valve 48. Switch 56 is connected to a source of electrical potential and connected by wiring to the coils of the electromagnet 26 and 28 respectively. There are means interlocking valve 48 and switch 56 for simultaneous operation, and these means may be represented by a single lever 58 mounted on a pivot and pivotally connected to the valve and switch actuators. In the forms of my invention using one or more cylinders instead of screws 38 and 40, the additional cylinder or cylinders control valve assembly may also be interlocked with lever 58 or may be separately controlled, as desired. Also, the force between magnets 26 and 28 may be used to punch work piece W, in which case the cylinder 34 and its control 48 may be omitted in favor of a tool holder secured to plate 22 or the upper magnet.

Optimum flux path properties are established by the width of the gap between pole pieces of the electromagnets 26 and 28, the permeability of the metal thereof including plates 36 and 42, and the operating current energizing the coils. High magnetic attraction across the throat of press 10 is obtainable by using upper and lower electromagnets. In those instances where the highest magnetic attraction is not necessary and where economy is important, two of the coils, for instance the coils of electromagnet 26, may be omitted so that the remaining cores and plate 36 function as a flux return for electromagnet 28. Other variations are contemplated by my invention. For instance, the invention may be embodied as an attachment composed of one or more electromagnets attached to an otherwise conventional press across the throat thereof and this will have the effect of increasing the useful force capacity of the conventional press. Permanent magnets may, also, be employed with flux shunting arrangements used to energize or reduce the flux in the working gap as is done in magnetic clutches. These are well known and need not be described here.

Other modifications as fall within the scope of the following claims, may be resorted to without departing from the protection afforded by the claims.

I claim:

1. A press comprising a rigid frame having a rear

frame member, upper frame member stationarily fixed to said rear frame member, and a lower frame member stationarily fixed to said rear frame member, said frame being incapable of sufficiently and effectively resisting a given reactive press force applied in a direction tending to spread said upper and lower members, said upper and lower frame members defining a deep throat, tool actuating means reacting on said upper and lower frame members to function on a work piece in said throat, and magnetic means spaced from said rear frame member and operatively connected with said upper and lower frame members and providing a reaction for said force to prevent spreading of said throat when said tool actuating means are operative on a work piece and generate a force equal to said given reactive press force.

2. The press of claim 1 and control means interlocked with said tool actuating means for energizing said magnetic means.

3. The press of claim 2 wherein said magnetic means include an electromagnet, and means adjustably securing said electromagnet to one of said frame members.

4. A punch press comprising a tool holder and operating device; a first electromagnet; a second electromagnet opposing said first electromagnet; said electromagnets having opposite poles facing each other and having a flux gap therebetween, the space between opposing poles forming a work piece receiving station; means to energize said electromagnets; a base against which said device reacts and to which said second electromagnet is secured; and rigid mechanical means against which said device reacts; said mechanical means being structurally incapable of resisting normal reactive press forces generated by said holder and operating device without exceeding the elastic limit of said mechanical means or otherwise excessively spreading, to support said first electromagnet in opposing relation to said second electromagnet, whereby the magnetic attraction between electromagnets transmits press

reactive forces between said base and said mechanical means.

5. The press of claim 4 wherein said electromagnets constitute a work piece clamp; and interlocked means for operating said device and energizing said electromagnets.

6. A deep throat, lightweight press comprising a tool actuating device, a rigid frame having a back member, an upper member and a lower member fixedly secured to said back member and supporting said device, said upper and lower members defining a throat and being structurally incapable of preventing the throat from excessive spreading under a given maximum loading of said frame or otherwise structurally failing, and magnetic means spaced from said back member and operatively connected with said upper and lower frame members but leaving said throat completely open and transmitting press forces between top and bottom of said throat to prevent said spreading under the same given maximum loading of said frame.

7. An attachment for a press to increase the useful working force parameter of the press and wherein the press has a rigid frame provided with fixedly connected frame members defining a throat, said attachment comprising electromagnetic means connected with said frame members defining said throat for establishing a closed loop flux path across said throat to resist spreading the frame members under press loading by transferring press forces between the frame members, and means to control the energization of said electromagnetic means.
